UNITED STATES PATENT OFFICE

2,455,246

CAP APPLYING MACHINE

Carl W. Goodwin, Plainfield, N. J., and Harold W. Martin, Malverne, N. Y., assignors to American Seal-Kap Corporation of Delaware, Wilmington, Del., a corporation of Delaware

Application May 15, 1946, Serial No. 669,932

1 Claim. (Cl. 226—88.1)

1 This invention relates generally to machines of the type shown in the patent to Goodwin et al. No. 2,325,163, for applying flexible skirted hood caps about the mouths of milk bottles.

Cap applying machines of this type are used in conjunction with standard bottle filling and capping machines of the rotary type. These filling machines generally comprise a continuously rotating table and a bowl or container thereabove which rotates in unison with the table. The table has a plurality of stools, arranged in a circle, which are raised and lowered as the table rotates. Directly above each stool is a filling valve which projects down from the underside of the bowl. Empty bottles are fed by a suitable conveyor onto the stools in alignment with the valves thereabove. As the bottles are carried around upon the stools the stools are elevated, by suitable mechanism, which raises the bottles up into contact with the valves with the nozzles of the valves extending into the mouths of the bottles. When the bottles come into contact with the valves they open the valves allowing milk to flow from the bowl into the bottles. After the bottles have been carried around for a predetermined distance they are lowered and the filled bottles are then transferred from the filling section of the machine into the capping section where suitable caps are secured into and about the mouths of the bottles.

Standard filling and capping machines of this type are all constructed so that they may be adjusted to fill and cap different size bottles, such as quarts, pints and half pints. In smaller dairies the same machine is used to fill the different size bottles, which necessitates the adjusting of the machine after one size of bottles has been filled before it can be used to fill bottles of another size. Also, in dairies it is the general practice today to apply hood caps to bottles containing certain grades of milk and to apply plug caps to bottles containing other grades of milk. This practice also requires certain adjustments as the filling and capping machine is switched from one grade of milk to another.

When hood caps are used on bottles, the hood caps, after having been properly conditioned for application, are loosely applied to the mouths of the bottles as they are transferred from the filling section to the capping section. In the capping section the loosely applied caps are firmly secured in and about the mouths of the bottles.

The aforesaid Goodwin et al. Patent No. 2,325,163 relates to a machine for conditioning skirted hood caps and loosely applying them to the mouths of bottles as they are transferred from the filling

2

section to the capping section of the filling and capping machine. This machine must also be adjusted in conjunction with any change in the adjustment of the filling and capping machine as it is switched from one size bottle to another; and when hood caps are not used on the bottles, this machine must be moved out of operative relation with the filling and capping machine.

Our invention is an improvement of the machine disclosed in the Goodwin et al. patent and relates specifically to the mechanism for supporting the machine in operative relation to a capping and filling machine.

The principal object of our invention is to provide in a machine of this character means whereby it may be quickly and easily adjusted to conform to any change in the adjustment of the filling and capping machine with which it is associated.

20 Another object of our invention is to provide in a machine of this character means through which it may be quickly and easily moved into and out of operative relation to a filling and capping machine as the filling and capping machine is switched from one grade of milk to another.

Other and more limited objects of the invention will be apparent from the following specification and the accompanying drawings forming a part thereof wherein:

30 Fig. 1 is a plan view showing our improved hood cap conditioning and dispensing machine operatively associated with a standard filling and capping machine;

Fig. 2 is a side elevation of our improved cap conditioning and applying machine, looking from the position indicated by the line 2—2 on Fig. 1;

Fig. 3 is a front elevation of our improved machine, on a slightly larger scale than the scale of Fig. 2, looking from the position indicated by the line 3—3 on Fig. 1;

Fig. 4 is a sectional plan view taken on the line 4—4 of Fig. 3; and

Fig. 5 is a central vertical section taken on the line 5—5 of Fig. 3.

45 Referring now to the drawings by reference characters the numeral 1 indicates generally our improved cap conditioning and applying machine which is shown, in Fig. 1, operatively associated with a standard rotary filling and capping machine having a bottle filling section 2 and a capping section 3. The filling section generally comprises a rotating table 4 having a plurality of bottle supporting and elevating stools 5 arranged in a circle thereon, and a filling bowl 6 which is disposed above the table 4 and rotates in unison

therewith. The capping section 3 generally consists of a plurality of bottles supporting and elevating stools 7, which are arranged to be moved in a circular path, and a plurality of capping heads 8 disposed above the stools in alignment therewith and arranged to move in unison with the stools 7.

Empty bottles 9 are fed by a suitable conveyor 10 to a star wheel 11 which transfers the bottles from the conveyor 10 onto the stools 5. As the bottles are carried around on the stools 5 they are elevated into engagement with valves projecting down from the underside of the bowl 6 through which they are filled with milk from the bowl 6. After the bottles have been filled they are lowered and transferred by a star wheel 12 from the stools 5 onto the stools 7 beneath the capping heads 8. As the filled bottles are being transferred from the stools 5 to the stools 7, they pass a cap applying station 13 where properly conditioned hood caps 14 are loosely applied to the mouths thereof. In the capping section 3 the bottles are carried around in a circular path upon the stools 7, and as they are being carried around they are elevated into the capping heads 8 which firmly secure the caps 14 in and about the bottle mouths. After the caps 14 have been secured in place the bottles 9 are transferred by a star wheel 15 from the stools 7 back onto the conveyor 10.

The cap conditioning and dispensing mechanism is all mounted upon a plate 16, and since it is substantially the same as the mechanism disclosed in the aforesaid Goodwin et al. patent it need not be described in detail herein. It comprises generally a cap magazine 17, a discharge chute 18, a cap picker mechanism 19 and a conditioning chamber 20 which terminates at the cap applying station 13. The magazine consists of a plurality of tubes 21 in which nested stacks of caps are placed. The tubes 21 are successively brought into register with the discharge chute 18 down which the caps slide from the tubes 21. As the bottles are being carried around on the stools 5 they actuate an arm 22 which momentarily closes a switch 23. The closing of the switch 23 energizes a solenoid 24 which operates a one revolution clutch to connect the driving mechanism of the cap picker to a constantly rotating motor 25. The cap picker then withdraws the foremost cap from the discharge chute 18 and deposits it in the conditioning chamber 20. The caps are conveyed through the conditioning chamber 20, by suitable mechanism, and are discharged therefrom to the cap applying station 13 in the path of the filled bottles as they are being transferred from the filling section 2 to the capping section 3 of the filling and capping machine. As the caps are being conveyed through the conditioning chamber 20, they are properly conditioned for application to the mouths of the bottles.

The plate 16 is slidably mounted as indicated at 26 upon the upper surface of a gear case 27 which is secured to the upper end of a vertically extensible and contractable pedestal generally indicated by the numeral 28. A rack 29 which is secured to the underside of the plate 16 meshes with a gear 30 within the case 27. The gear 30 is keyed to a shaft 31 rotatably supported by suitable bearings 32 mounted in the side walls of the gear case 27. The shaft 31 and the gear 30 thereon are adapted to be rotated by a crank 33 which is removably secured to the projecting end of the shaft 31. Rotation of the shaft 31 will move the

plate 16, and the mechanism secured thereto, back and forth upon the gear case 27. A removable plate 34 closes the upper end of the gear case 27.

5 The pedestal 28 has a base 35 which is supported by adjustable legs 36. The base 35 is made of cast iron and is so proportioned as to weight and size that all danger of the apparatus tipping over is obviated, regardless of the adjustment thereof. A centrally disposed sleeve, having a vertical bore 37 therein, is cast integrally with the base 35 and extends upwardly and downwardly from the top wall of the base as indicated at 38 and 39. A tube 40 is slidably mounted in the bore 37 and is prevented from turning therein by cooperating keys and keyways 41 and 42 respectively. A cylindrical boss 43 which is secured to the underside of the gear case 27 projects downwardly therefrom into the upper end of the tube 40 and is securely fastened therein. A vertical shaft 44 is rotatably supported in an axial bore 45 in the boss 43 by bearing 46. The upper end of the shaft 44 extends into the gear case 27 and has a bevel gear 47 keyed thereon. The gear 47 meshes with a bevel gear 48 which is keyed to the inner end of a shaft 49 which is rotatably supported by bearings 50 and 51 suitably mounted in the gear case 27. A crank 52 is removably secured to the outer end of the shaft 49. The lower end of the shaft 49 is threaded as indicated at 53 and extends through a nut 54 which is rigidly secured in the upper end of a member 55. The member 55 is disposed within the lower end of the bore 37 and is rigidly secured at its lower flanged end 56 to the base 35 by studs 57. The base 35 is strengthened by ribs 58 and the lower end thereof is closed by removable plates 59 and 60. A telescoping shield composed of upper and lower sections 61 and 62 surrounds the projecting end of the tube 40 and the upper end 38 of the base sleeve. The shaft 44 is rotated by the crank 52 through the shaft 49 and the bevel gears 48 and 47. Rotation of the shaft 44 in the nut 54 will vertically extend or retract the pedestal 28 depending on the direction of rotation of the shaft 44, as is clearly apparent in Fig. 5. Vertical adjustment of the pedestal 28 will raise or lower the cap dispensing and conditioning apparatus supported thereon.

When the adjustment of the filling and capping machine is changed to accommodate it to different size bottles, the cap dispensing and conditioning apparatus can be correspondingly adjusted quickly and easily by merely turning the shaft 49 in the proper direction by the crank 52, and the cap dispensing and conditioning apparatus can be quickly and easily moved into and out of proper operative relation with the filling and capping machine by rotating the shaft 31 in the proper direction by the crank 32.

60 From the foregoing it will be apparent to those skilled in this art that we have provided a simple and efficient apparatus for accomplishing the objects of our invention; and it is to be understood that we are not limited to the specific construction shown and described herein as various modifications may be made thereto within the scope of the appended claim.

What is claimed is:

70 A bottle capping machine comprising a base, a vertical bore in said base, a tube slidably keyed in said bore, a gear case secured to the upper end of said tube, a plate slidably mounted on said gear case, a cooperating rack and pinion for moving said plate back and forth on said gear case, a cap dispensing and conditioning mechanism carried

by said plate, a screw shaft rotatably supported in the upper end of said tube with the upper end thereof extending into said gear case, a nut through which said screw shaft extends rigidly secured to said base within said bore, a bevel gear keyed to the upper end of said screw shaft, a co-operating gear keyed to a shaft rotatably mounted in said gear case and meshing with said bevel gear, and means for rotating said shaft to raise and lower said tube within said bore.
